(57) **CLAIM**

The ornamental design for a vehicle-traveling tent, as shown and described.

DESCRIPTION

FIG. 1 is a front, right, and top perspective view of a vehicle-traveling tent, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right, and top perspective view of the vehicle-traveling tent in FIG. 1 showing a state on a vehicle; and,

FIG. 10 is a partial enlarged view of an area labeled 10 in FIG. 1 showing a lower right corner of the vehicle-traveling tent and a tape.

The broken lines shown in the drawings are included for the purpose of illustrating portions of the vehicle-traveling tent that form no part of the claimed design.
